CRACKING PROCESS

Kenneth M. Watson, Chicago, Ill., assignor to
 Universal Oil Products Company, Chicago, Ill.,
 a corporation of Delaware

Application September 20, 1940, Serial No. 357,523

7 Claims. (Cl. 196—49)

This invention relates to a process for converting hydrocarbon oil into substantial yields of gasoline and gas. More particularly it relates to the cracking of hydrocarbon fractions in the presence of a powdered catalyst to produce substantial yields of high antiknock gasoline.

The charging stock used in the present invention is normally from petroleum sources and includes distillate fractions of straight run and cracked hydrocarbon oils such as kerosene, gas oil, wax distillate and the like, as well as higher boiling fractions including topped crude oil, reduced crude oil, etc. Similar suitable charging stocks from other hydrocarbon sources may also be converted.

In one specific embodiment the present invention comprises treating a distillate fraction of hydrocarbon oil in a primary cracking step with a powdered catalytic agent under cracking conditions of temperature and under a pressure adequate to maintain a major portion of the oil boiling above the gasoline range substantially in liquid phase, continuously recycling a portion of said oil containing catalyst in suspension to the catalytic reaction zone, passing a second portion of liquid reaction products substantially separated from said catalyst to a secondary cracking step wherein it is subjected to further treatment with a powdered cracking catalyst together with a higher boiling fraction of hydrocarbon oil than is used in said primary cracking step, continuing said treatment at a cracking temperature and under pressure adequate to maintain higher boiling reaction products substantially in liquid phase, separating and recycling a portion of said catalyst suspended in oil, separating a further fraction substantially free of catalyst, subjecting it to a vaporizing step and returning a portion of the vapors therefrom for further cracking in said primary step, separately fractionating the vaporous reaction products from said primary and said secondary steps and recovering the gasoline and gas formed.

The invention is further understood by reference to the accompanying drawing which is diagrammatic and should not be interpreted as limiting the process unduly.

A hydrocarbon oil fraction which may comprise a distillate fraction of petroleum oil such as naphtha, kerosene, gas oil, wax distillate, etc., is introduced to the primary cracking step through line 1, valve 2, pump 3 and valve 4 to coil 5 which is contained in heater 6. A powdered catalytic agent is introduced from catalyst charger 7 through line 8, valve 9, pump 10 and

valve 11. The quantity of catalyst introduced may be from approximately 0.1-10% by weight of the charge and is preferably of the order of 0.1-2% although larger amounts may be used, for example, up to 10%. Any suitable cracking catalyst powder may be used, such as, for example, silica-alumina, silica-zirconia, silica-alumina-zirconia and similar catalysts as such or having deposited thereon relatively minor quantities of promoting compounds such as an oxide of chromium, molybdenum, tungsten, uranium, titanium, etc. These catalysts are prepared by the separate or simultaneous precipitation of the components under conditions such that a powder approaching colloidal dimensions is obtained. The powder may be further washed to remove sodium compounds.

Another type of catalyst which may be used comprises a relatively inert carrier such as alumina, silica, magnesia, titania, zinc oxide and the like, having deposited thereon promoting oxides of elements appearing in the left-hand column of the IVth, Vth and VIth groups of the periodic table. Still another type of catalyst is naturally-occurring earths which may have been further activated by treatment with mineral acids or other chemical agents.

These catalysts, or mixtures thereof, have been found to be suitable in the process but are not necessarily equivalent in their action and should not be so construed.

The mixture is heated to a temperature within the range of approximately 500-1200° F. and pressure from approximately 50-1000 pounds per square inch or higher. The heated products pass through line 12 and valve 13 to reaction chamber 14. The reactor is normally maintained at a temperature within the range of approximately 500-1200° F., the pressure being adequate to maintain a major portion of the liquid reaction products boiling above the gasoline range substantially in liquid phase. A vaporous fraction consisting substantially of gasoline and gas is removed through line 15 and valve 16 to fractionator 17, from which gas and gasoline are recovered, through line 18 containing valve 19, condenser 20 and valve 21. The gasoline is collected in receiver 22 and may be removed to a suitable stabilizer through line 23 containing valve 24. Receiver gases are passed to a gas recovery system through line 25 and valve 26. Higher boiling oil may be withdrawn through line 27 and valve 28, but is normally recycled through line 30, valve 31, pump 32 and valve 33, joining with the charging stock to the primary

cracking step in line 1. A portion of liquid reaction products are removed from reaction chamber 14 through line 34 and valve 35 to separator 36. This comprises a settling chamber maintained at superatmospheric temperature wherein the powdered catalyst is allowed to settle and concentrate in a portion of the reaction products which are withdrawn through line 37, valve 38 and pump 39, a portion being returned to the reaction zone through line 40 and valve 41 in order to build up and maintain a higher percentage of catalyst in the reaction zone than is charged with the incoming oil. A portion of the oil containing catalyst in suspension is removed through line 42 and valve 43 to a suitable catalyst recovery system. The catalyst may then be reactivated by contact with an oxygen-containing gas and may be used in this or in the secondary cracking step about to be described for further converting hydrocarbon oil to gasoline.

The portion of oil at the top of the settler, being substantially free of catalyst, is passed through line 44 containing valve 45, pump 46 and valve 47, joining with line 48 containing valve 49 and being passed to coil 50 which is disposed in heater 51. The oil is mixed with the charging stock for the secondary cracking step, entering through line 52 containing valve 53, pump 54, and valve 55. Powdered catalytic agent is introduced from catalyst charger 56 through line 57, valve 58, pump 59 and valve 60. The catalytic agent used in this step may, as previously indicated, be a portion of the reactivated catalyst from the primary step or may comprise any one of the catalysts previously mentioned or a mixture of such catalysts. It need not be the same catalyst employed in the primary step. Thus, for example, the highly active silica-alumina type catalyst may be used in the primary step for converting gas oil, while a less reactive catalyst such as a naturally-occurring earth may be used in the secondary cracking step. Furthermore, a catalyst which has been used a number of times in the primary step and has been reduced in activity, may be used in the secondary cracking step. The conditions of cracking employed in the secondary cracking step are somewhat milder than those used in the primary step because of the heavy character of the charging stock which may comprise heavy distillate fractions or such fractions of crude petroleum oil as topped crude oil or reduced crude oil. The temperature is within the range of approximately 500-1000° F. or slightly higher and the pressure is within the range of approximately 50-1000 pounds per square inch, being, as in the primary step, adequate to maintain a substantial portion of the reactants in liquid phase.

The mixture passes through line 61 and valve 62 to reaction chamber 63, which is maintained within the region specified and vaporous reactants containing substantial quantities of gasoline may be removed through line 64 and valve 65 to fractionator 66. The gasoline and gas are recovered through line 67, valve 68, condenser 69 and valve 70, entering receiver 71 from which the gasoline may be removed through line 72 and valve 73 to a suitable stabilizer not shown. Receiver gases may be removed to a gas recovery system not shown through line 74 and valve 75. The fraction boiling above the gasoline range is passed through line 76, valve 77, and valve 77' to line 48 containing pump 78 and thus returned through valve 49 to coil 50. Liquid reaction products are removed from reaction chamber 63

through line 79 and valve 80 to separator 81. As in the case of separator 36, the catalyst separates by gravity, concentrating in the oil in the lower part of the separator. A portion may be removed through line 82 containing valve 83 and pump 84, being recycled through line 85 and valve 86 to the reaction chamber in order to build up the amount of catalyst therein from the amount charged which is of the order of 0.1-10%. A portion of oil may be removed through line 87 and valve 88, the catalyst being recovered therefrom and separately reactivated or discarded as the case may be. The portion of liquid reactants substantially free of catalyst is removed through line 89, valve 90, heater 91 and valve 92 to vaporizing chamber 93. A residue unsuitable for further conversion may be withdrawn through line 94 containing valve 95. The vaporous fraction is removed through line 96 and may be recycled in part through line 97 containing valve 98 joining with line 48 and thus being returned to the coil. An additional quantity of oil suitable for fuel purposes may be removed through line 99 and valve 100. As an alternative, a portion of the reactants from lines 76 and 97 may be passed through line 101 containing valve 102, pump 103 and valve 104 to line 30 and thus passed to the primary cracking step. The following example is given to illustrate the practicability of the process, but should not be construed as limiting it to the exact conditions, catalysts, or oils indicated therein.

When cracking gas oil in the primary cracking step and reduced crude oil in the secondary cracking step at a temperature of 975 and 850° F., respectively, a total yield of 65% of cracked gasoline having an octane number of 78 may be obtained. In addition, relatively minor amounts of products valuable for fuel purposes are produced. The catalyst employed in the primary cracking step may comprise silica-alumina and that employed in the secondary cracking step may be a naturally-occurring earth which has been activated by treatment with mineral acid.

I claim as my invention:

1. A conversion process which comprises cracking hydrocarbon distillate in admixture with powdered cracking catalyst under sufficient pressure to maintain a substantial portion of the hydrocarbons in liquid phase, independently cracking a hydrocarbon oil of higher boiling point than said distillate in admixture with powdered cracking catalyst and under sufficient pressure to maintain a substantial liquid phase, separating from the unvaporized products of the first-named cracking step a light residual oil substantially free of catalyst and supplying the same to the second-mentioned cracking step, separating from the unvaporized products of the second-mentioned cracking step a hydrocarbon fraction substantially free of catalyst, supplying at least a portion of said fraction to the first-named cracking step, and recovering gasoline from the vaporous products of said cracking steps.
2. The process as defined in claim 1 further characterized in that said fraction is subjected to vaporization and hydrocarbons thus vaporized supplied to said first-named cracking step.
3. A conversion process which comprises cracking hydrocarbon distillate in admixture with powdered cracking catalyst under sufficient pressure to maintain a substantial portion of the hydrocarbons in liquid phase, independently crack-

- ing a hydrocarbon oil of higher boiling point than said distillate in admixture with powdered cracking catalyst and under sufficient pressure to maintain a substantial liquid phase, separating from the unvaporized products of the first-named cracking step a light residual oil substantially free of catalyst and supplying the same to the second-mentioned cracking step, separating from the unvaporized products of the second-mentioned cracking step a hydrocarbon fraction substantially free of catalyst, vaporizing a portion of said fraction and supplying resultant vapors to the first-named cracking step, and recovering gasoline from the vaporous products of said cracking steps.
4. A process for converting hydrocarbon oil into substantial yields of gasoline which comprises treating a lower boiling fraction of hydrocarbon oil in a primary cracking step with a powdered catalytic agent under cracking conditions of temperature and a pressure adequate to maintain a substantial portion of oil boiling above the gasoline range in liquid phase, recovering gasoline and gas, subjecting the liquid fraction of conversion products containing catalyst in suspension to a separating step, recycling to said primary step a portion of said liquid fraction containing catalyst in suspension, passing a further portion of said liquid fraction substantially free of catalyst to a secondary cracking step together with a higher boiling fraction of petroleum oil and a powdered catalytic agent, maintaining the mixture at catalytic cracking conditions of temperature and under pressure adequate to maintain a substantial portion of higher boiling reactants in liquid phase, recovering gas and gasoline therefrom, subjecting unvaporized products of the secondary cracking to a separating step, recycling to said secondary cracking step a portion of said unvaporized products containing catalyst in suspension, passing a portion of said unvaporized products substantially free of catalyst to a vaporizing zone, withdrawing a residual fraction unsuitable for further conversion and passing at least a portion of the vaporized product from said vaporizing zone to the aforesaid primary cracking step for further conversion.
5. A process for converting hydrocarbon oil into substantial yields of gasoline which comprises treating a lower boiling fraction of hydrocarbon oil in a primary cracking step with a powdered catalytic agent under cracking conditions of temperature and a pressure adequate to maintain a substantial portion of oil boiling above the gasoline range in liquid phase, recovering gasoline and gas, subjecting the liquid fraction of conversion products containing catalyst in suspension to a separating step, recycling to said primary step a portion of said liquid fraction containing catalyst in suspension, passing a further portion of said liquid fractions substantially free of catalyst to a secondary cracking step together with a higher boiling fraction of petroleum oil and a powdered catalytic agent, maintaining the mixture at catalytic cracking conditions of temperature and under pressure adequate to maintain a substantial portion of higher boiling reactants in liquid phase, recovering gas and gasoline therefrom, subjecting unvaporized products of the secondary cracking to a separating step, recycling to said secondary cracking step a portion of said unvaporized products containing catalyst in suspension, passing a portion of said unvaporized products substantially free of catalyst to a vaporizing zone, withdrawing a residual fraction unsuitable for further conversion and passing at least a portion of the vaporized product from said vaporizing zone to the aforesaid primary cracking step for further conversion.
6. The process as set forth in claim 4 wherein the catalytic agent employed in the primary cracking step has greater activity than that employed in the secondary cracking step.
7. The process as set forth in claim 4 wherein the temperature employed in the primary cracking step is from about 500 to about 1200° F., and the temperature employed in the secondary cracking step is from about 500 to about 1000° F., the pressures in each step being from about 50 to about 1000 pounds per square inch.
